(57) **CLAIM**

The ornamental design for an augmented junction box, as shown and described.

DESCRIPTION

FIG. 1 is a front perspective view of an ornamental design for an augmented junction box;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in the figures represent portions of the augmented junction box that form no part of the claimed design.
